MEANS FOR ERECTING PRECAST WALLS

Orlo A. Bartholomew, Riverdale, Md.

Application September 3, 1953, Serial No. 378,389

1 Claim. (Cl. 214—1)

This invention appertains to improvements in present methods and means for raising precast walls from a horizontal position on the site to a vertical set in place position.

All of the conventional methods and means for erecting such structures, while differing somewhat in details and procedures, have in common certain disadvantages, such as the use of mobile cranes, requiring a highly paid operator and a large crew, necessitating moving the crane each time a wall is lifted and requiring a large amount of room for manipulation of the crane, which, furthermore, cannot operate during inclement weather. Additionally, with a mobile crane, the point of lift is not from a rigid support.

Most constructions require the use of large cranes, since simple equipment such as hand-operated inside tilting masts, are only operationally feasible when small panels are being erected. However, it has been found that a lift from inside the structure is more efficient but, with panels of any appreciable size, such inside lift cannot be presently achieved since cranes and other heavy equipment, which are required to provide the lifting force, cannot be positioned inside a building for they will overstress the floor. Also, even with small panels in the erection of small buildings, tilting from the inside with small equipment, that will not overstress the floor, has a tremendous disadvantage, since such equipment will cause interference with other construction work. Thus, though a lift from the inside is known to be the most advantageous, no present method or means has been provided to realize it without the disadvantages referred to above.

Therefore, the primary object of my invention is to provide a method and means for obtaining an inside lift which method and means can be employed with panels of any type or size in the erection of large or small buildings.

A further object of my invention is to provide a rigidly supported hoist means so that the point of lift is from a rigid support and to provide means for moving leads from the hoist means as the panels are erected.

A further object of my invention is to provide a frame which can be easily and inexpensively erected over the floor in a manner to enclose the building and which will support the leads in an adjustable manner so that the leads can be moved from an erected panel longitudinally or transversely of a building to be attached to a horizontally disposed adjoining panel. In this regard, the point of lift remains rigidly fixed and the leads are moved along the frame to be attached to subsequent panels.

A still further object of my invention is to provide a cover for the frame so that the building is covered against inclement weather to make it possible to maintain an uninterrupted working schedule.

A still further object of my invention is to provide a new method and means for tilting the walls or panels

2

from horizontal positions to erected vertical positions and also for lifting the panels from horizontal positions to vertical in place positions, which method and means embody a rigid hoist that is connected to the panels by adjustable leads which are carried by a framework enclosing the building.

These and ancillary objects are attained by this invention, the preferred embodiments of which are set forth in the following description and illustrated in the accompanying drawings, wherein:

Fig. 1 is an end elevational view of the frame-work enclosing the building, which is diagrammatically shown, the wall panels being shown in end elevation resting horizontally on the floor and shown in dotted lines in their subsequent partly raised and set in place positions, achieved by means of the leads from a fixed hoist means;

Fig. 2 is a side elevational view of the frame-work;

Fig. 3 is a sectional plan view taken on line 3—3 of Fig. 1 and showing one of the panels resting horizontally on the floor, and showing the manner of attaching a lead to the panel;

Fig. 4 is a detailed vertical cross-sectional view taken on line 4—4 of Fig. 3;

Fig. 5 is a detailed fragmentary vertical sectional view taken on line 5—5 of Fig. 2, and

Fig. 6 is an enlarged detailed showing of the castor means on the lower end of one of the panels which is raised to a vertical set in place position.

Referring now more particularly to the accompanying drawings, the numeral 10 designates a building which is constructed by having its walls cast on the site in a horizontal position, erected to a vertical set in place position and made an integral part of the structure.

Such construction involves the placement of a form on the concrete floor slab 12, after bond preventative material has been spread on the slab and the pouring of concrete in the form to make the wall panel. There are many methods and means for so forming the panel, but this invention is applicable to wall panels irrespective of their construction. After the panel is finished, it is raised from its horizontal position on the floor slab conventionally by cranes outside the building or by small inside equipment, useable only with small panels, to a vertical position. It is braced in such position until connecting columns or the like securing means, which is the final operation, are poured and which are in many differing ways, structurally made a part of the erected panels.

The present invention is primarily concerned with the provision of means for erecting or raising the wall panels and such means embodies a frame or frame-work 14. The frame 14 is mounted so that it straddles the building and includes a number of longitudinally spaced inverted substantially U-shaped struss members or arches 16.

Each arch includes a pair of complementary channel shaped sections 18 and 20, which are identically formed and have vertical sections or standards 22, 24 and upwardly inclined, inwardly directed ends 26, 28.

The standards are suitably anchored on footings 30 formed alongside and spaced outwardly from the floor slab 12 and are vertically positioned alongside the building. Reinforcing webs 32 are provided between the upper portions of the vertical sections or standards 22, 24 and the ends 26, 28. The terminal portions of the ends are overlapped and are formed with axially spaced openings 31, 33 to receive a connecting and securing fastener 34.

The terminal portions are held together by a connecting plate 36 that has crossed channels 38 and 40 to receive the portions and has a central opening to receive the fastener. The purpose of the plate is to rigidify the ends 26 and 28 and the spaced openings 31 and 33 are

provided so that the distance between the standards can be adjusted in conformance with the dimension of a building therebetween.

One manner of raising the wall panels is shown in connection with the right side wall panel 42 of Fig. 1, wherein the panel has its exterior surface lying flat on the floor 12 and the panel is pulled upwardly about its lower end 44 into a vertical set in place position. The panel 42 is formed of any desired materials which are molded within a form 46 on the floor 12.

A connecting member 48 for a lift (not shown) lead 50 is releasably attached to the form and spans the interior surface 52 of the panel. The connecting member, as shown in Figs. 3 and 4, includes a pair of parallel cross bars 54 and 56 which are connected by rigidifying center and end bars 58, 60 and 62, respectively, that extend longitudinally of the panel 42. The ends of the bars 54 and 56 overhang the sides of the panel and are secured by J-bolt 64 to the form. In this fashion, the lifting stress of the lead 50 is transferred longitudinally and transversely of the form, which cradles the panel. Lifting stresses on the panel are eliminated due to the transfer of stress on the form and also because no attachment is made to the finished wall surface. Of course, the connecting means can be easily adjusted to fit panels of varying widths by providing simple telescopic or extensible extensions for the bars 54 and 56.

Eyes 66 or similar structural elements are received at the center line of the connecting means and, as shown in Fig. 3, are attached to the bar 54 at its center and to the projecting upper end of the center bar 58. The eyes 66 receive the eye ends 68 of a flexible member 70, on which a pulley 72 rides. The pulley is attached by its holder 74 to the lead 50, which extends from a rigidly supported and fixedly located winch, preferably positioned outside the other side of the building, though it may easily be set up within the building.

I beam 76 is secured to the ends 26 of the arches, as shown, for example in Figs. 1 and 5. The I beam, which extends longitudinally of the building and transversely of the arches, is preferably located at the center of the arches and on the ends of each section of an arch above the webs 32. Rollers 78 and 80, mounted on a common shaft 82, are rotatably positioned on the upper surface of the lower horizontal flange 83 of the I beam. The shaft 82 extends through the free ends of a U-shaped holder 84 which supports a guide pulley 86 at its web, the pulley being arranged at right angles to the rollers or paralleling the arches. The lead 50 is reeved over the pulleys on the I-beam and is thereby supported by the arches between the panel and the lift, that is the winch.

In this respect, one advantage of the guide pulleys 86 being mounted for movement longitudinally of the building resides in the fact that the point of lift remains fixed and rigid, while the lead can be moved along to be attached by the connecting means to other adjoining panels.

From the prone position, full line position of Fig. 1, the panel 42 is raised by the lead 50, as it is wound on the winch, to the half-raised position indicated by dotted lines. In moving, it will be noted that the lower end 44 of the panel has to slide on the floor 12 and to enable the sliding action to be performed easily, without frictional drag and without damage to such end, a center roller support 88 is provided. As shown in detail in Fig. 6, the roller support 88 includes a U-shaped bracket 90 which has its legs fitted over the form and interior surface of the panel. The leg overlying such panel surface carries a set screw 92 to lock the bracket in place. An arm 94 projects from the web and carries a roller 96, which is adapted to roll on the floor, as shown in Fig. 1. As the panel is pulled upwardly, the pulley 72 rides upwardly and outwardly on the flexible member 70 and the roller 96 rolls on the floor. A direct vertical pull is imparted to the form and panel due to the fact that the

guide pulley 86 lies directly in the vertical plane which the panel will occupy when it is in its erected or set in place position.

Thus, the flexible member 70 and the pulley 72 on the end of the lead 50 and the guide pulley 86 in its relative position to the panel are of utmost importance in insuring that a smooth, friction free vertical pull will be exerted on the form and panel. By having the guide pulley 86 directly overhead, the lifting starts from a vertical position rather than at an angle as is necessary when the equipment is outside the building. Such vertical lift is maintained from the prone to the upright, erected position of the panel due to the guide pulley 86 and the flexible member 70 and the lead pulley 72.

When the panel is in a vertical position, it is raised so that the roller support 88 can be loosened and knocked off. Then, the panel is lowered till its lower end 44 sets in place. Conventional stabilizing means are then used to support the panel in such position with the connecting member 48 being removed by loosening the J-bolts 64. The next panel can then be raised and erected in the same manner.

In Fig. 1, considering the left side wall panel 100, a tilt-up means is illustrated, which while slightly differing in structural details from the lift up means hereinbefore described, involves the essential inside and vertical lift method from a rigid, fixed winch by means of the frame work 14 and the use of the connecting member 48^a, shown diagrammatically, and the lead line 50^a and its pulley 72^a and flexible member 70^a (shown diagrammatically so as to not confuse the illustration and identical to the showing in connection with panel 42).

The panel 100 has its lower end positioned horizontally above its seat, whereas the lower end 44 of the panel 42 is moved from a position inwardly of the floor 12 to its seat at the outside thereof. The connecting member 48^a is, therefore, attached to the form at the upper end thereof and spans the exterior surface of the panel.

The lead 50^a is reeved on guide pulleys 102 and 104 which are carried by and depend from a carrier 106. The carrier is flexible and inherently resilient and is slidably disposed on one section of the arch to slide from the end 28 down to assume a vertical position on the standard 24. Suitable conventional locking means may be employed to lock the carrier in place, though the frictional force exerted under the resilient tension of the carrier will be sufficient to hold it in selected positions, such tension being overcome by manual force, directly applied or indirectly applied by means of a cable.

The carrier 106, when the panel 100 is in its prone position, is positioned directly over the center thereof between its ends, so that the lead 50^a extends slightly outwardly from the panel. This outward relation of the lead to the panel is maintained throughout the lifting of the panel (see the relative dotted line position of the panel and carrier in Fig. 1) until the panel is in its final, erected position.

The carrier thus insures that a pull inside the building is exerted on the panel from a fixed lift as the panel is tilted up to its vertical position.

With either the lift or tilt means, it is to be noted that the pull is always continuous and smooth so that the panel or its form are not over-stressed and that the guide means for either the lead 50 or 50^a enable an inside pull to be exerted on the panels from a fixed lift, which may be positioned inside the building or outside. Regardless of the site of the lift, the pull by the lead is from inside. Only the winch would be outside, all other hoist equipment being inside and being supported by the frame-work 14.

In this respect, to provide a continuous and uninterrupted work schedule, which is presently interrupted by rain, bright sun and the like weather forces, a tarpaulin 108 is provided and is stretched over the frame-work. If desired, it may even be extended to enclose the winch

and preferably would be so extended. The tarpaulin overlies the center of the arches and is stretched taut above the arches and anchored, in a conventional manner, to the ground. Only an extremely strong wind would cause any stoppage of work.

The first step in forming the building is the conventional one of pouring the floor slab 12 and then the footings for the arches are poured and the arches are erected. The wall panels are then formed and erected in place, after which any type of roof is secured to the wall panels. The arches are then dismantled and removed.

While the best known form of my invention has been shown in the drawings and described herein, other forms may be realized as come within the scope of the invention defined by the appended claim.

I claim:

In an apparatus for erecting rigid wall panels in forming the walls of a building comprising at least a pair of spaced parallel substantially U-shaped members adapted to be mounted in a position straddling a building, each 20 of said U-shaped members comprising substantially vertical legs and upwardly and inwardly extending end portions forming an apex, a connecting and securing plate for receiving the end portions at said apex, said end portions each having spaced aligned openings, a fastener pass- 25

ing through openings in said end portions and an opening in said plate whereby the height and width of said U-shaped members may be adjusted, a beam rigidly connected to said members inwardly and adjacent the vertical legs of adjoining members, and extending transversely thereof, a carrier slidably carried by said beam and including a pulley rotatable about an axis paralleling said beam, a rigid support adapted to be secured to a wall panel, and a lead reeved over the pulley on said carrier, 10 means connecting said lead at one end to said rigid support and adapted at the other end to be connected to a windlass.
